CIGARETTE CASE

Georg Reitzel, Altenmittlau, Kreis Gelnhausen, Germany,
assignor of one-half to Drescher & Kiefer, Altenmittlau,
Kreis Gelnhausen, Germany, and one-half to Randolph-
Rand Corporation, New York, N.Y., a corporation of
New York

Filed Mar. 26, 1963, Ser. No. 74,147

Term of patent 14 years

(Cl. D85—2)

FIG. 1

FIG. 4

FIG. 1 is a front elevational view of a cigarette case showing my new design;

FIG. 2 is a side elevational view, the opposite side being a mirror image of the side shown;

FIG. 3 is a rear elevational view; and

FIG. 4 is a top plan view thereof.

The characteristic feature of my design resides in a cigarette case the lid of which has the particular configuration and appearance shown herein.

I claim:

The ornamental design for a cigarette case, as shown and described.
